INVENTOR.

Joseph H. Pope.

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOES.

Application filed September 8, 1919. Serial No. 322,522.

To all whom it may concern:

Be it known that I, JOSEPH H. POPE, a citizen of the United States, residing at Hamilton, in the county of Essex and State of Massachusetts, have invented certain Improvements in Machines for Operating on Shoes, of which the following description, in connection with the accompanying drawings, is a specification, like reference characters 10 on the drawings indicating like parts in the several figures.

This invention relates to machines for operating upon shoes, being especially applicable to heel-attaching machines. Objects 15 of the invention are to increase the capabilities of such apparatus and to insure against accident through negligence in their operation.

In the attainment of these objects, I provide as a feature of the invention novel means for preventing interference with objects being transferred to a holding device, by a member for operating upon said objects, this means, in the performance of its 25 functions, being arranged to move the operating member out of the path of the objects. Preferably this movement is effected by connection to the mechanism which accomplishes the transfer. As herein illustrated in 30 the application of the invention to a heel-attaching machine, a block carrying drivers for operating upon nails held in a die or nail block is mounted to slide upon a reciprocating head by connections to an oscillatory loader mechanism which delivers nails to the nail block.

As a further feature of the invention, I have combined with an operating member having independent movements, for example 40 those previously indicated, an actuating mechanism for producing one of the movements, together with novel means for both controlling the actuating mechanism and effecting the other movement of the operating member. This common means is preferably 45 in the form of a transfer mechanism delivering to the holding device, there being connections between the transfer mechanism and the operating member and actuating 50 mechanism. The heel-attaching machine of the present disclosure has a reciprocating head upon which a driver block is mounted

to move and actuating mechanism for the head, there being a latch for the actuating mechanism, and a movable member, as the 55 loader mechanism, connected to the latch and block for actuating them.

Still another feature of the invention concerns the protection of the parts from breakage, as a result of a holding device which is 60 movably supported being out of correct alinement with the mechanism operating upon the objects held. In the attainment of this, I furnish means for retaining the holding device against movement and control 65 by said means the actuating mechanism for the operating member. Thus, in securing the nail block of the heel-attaching machine upon its support, its latch may engage means which controls the mechanism for applying 70 power to the drivers.

In the accompanying drawing,

Fig. 1 shows in perspective the upper portion of a heel-attaching machine to which one embodiment of my invention is applied; 75

Fig. 2 is a detail in vertical section through the latch for the starting lever, under the control of the loader mechanism;

Fig. 3 is a detail in horizontal section through the latch for the nail block; and 80

Fig. 4 is a vertical transverse section on the line 4—4 of Fig. 3.

For the purposes of the present disclosure my invention is described as applied to a heel-attaching machine of the type which 85 is the subject of the patent to me, No. 446,885, granted February 24, 1891. At 10 appears a portion of the frame of the machine, in which are mounted to reciprocate vertical side rods 11, 12 carrying fast upon their 90 upper extremities a head furnished by a top girt 14. In ways 16 extending across the under side of the head there is mounted to slide a driver block 18 from which depends a set of drivers 20 registering in the reciprocation of the head with openings 22 in a die or nail block 24, this block being removably held in ways 26 in the frame. In attaching 95 heels to shoes this machine operates in the well-known way, the movable elements being actuated by power mechanism, as in the patent previously mentioned, under the control of a lever 25 fulcrumed upon the frame below the nail block and held in its inactive 100

position by a spring 27 connecting the lever and the frame. Nails are delivered to the openings 22 by loader or transfer mechanism including an arm having a portion 28 pivoted 5 about the rod 12 and an outer portion 30, which is guided in vertical ways 32 formed upon the arm portion 28. The outer section of the arm is shown as adjustably held in place by a set screw 34 threaded into the 10 arm portion 30 and passing through a slot in the portion 28. By shifting one part of the arm upon the other and fixing it in place with the set screw, the loader mechanism may be arranged to best deliver to nail 15 blocks of different heights. In a recess at the outer extremity of the loader arm is a loader block 38, provided with openings disposed as the nails are to be in the heel operated upon and movable by oscillation about 20 the rod 12 from a nail-receiving position, as illustrated in Fig. 1 of the drawing, to a nail-delivering position in which the loader block openings are alined with certain of those in the nail block. The nail-receiving 25 position of the loader arm is determined variably by a stop screw 40 threaded through the arm and contacting with a portion 42 of the frame. The nails in the loader block are supported by a pivoted shutter 44 latched 30 in its position below the openings in the block by a pin 46 depending from the loader arm and engaging a depression in the shutter. In the nail-delivering position an inclined face of a projection 48 upon the shutter comes 35 into contact with a tripping projection 50 extending above the nail block, this releasing the shutter from the pin 46 and permitting a spring 52 surrounding the pivotal point of the shutter to withdraw it from beneath the loader block, allowing the nails 40 to fall into the openings 22 in position for driving. Sometimes nails are thrown from the loader block crossways upon the nail block, either by the jar produced by the stopping of the loader arm at the end of the delivery movement or because the nails had been dropped across the top of the loader block instead of in its openings. Nails thus disposed upon the nail block may be struck 45 by the drivers, which are thus broken. To prevent this, I fix across the front of the loader arm a clearing member furnished by a brush 53. This, sweeping over the nail block during the return of the loader arm 50 to its receiving position, effectively removes therefrom such misplaced nails.

When long nails are to be driven, their projection above the loader block may be so great that the drivers 20 in their normal 55 positions extend into their path of movement, preventing delivery to the openings 22. This difficulty I obviate by moving the driver block 18 in the ways 16 in advance of the nails during their delivery to the nail block. For this purpose, the portion 28 of

the loader arm carries a vertical rod 54 passing through a segmental slot 56 in a projection from the rear of a sleeve 58 surrounding the side rod 12. This sleeve is mounted upon the outside of a bearing sleeve 60 about the side rod 12, this last-mentioned sleeve being flanged at its lower end to support the sleeve 58 and being secured to the top girt by a set screw 62. From the front of the sleeve 58 project lugs 64 connected by 70 a link 66 to the adjacent edge of the driver block. Through the link is shown threaded a screw 67 arranged to contact at its inner end with the surface of the sleeve 58. By this screw, the extreme position of the driver block toward the right as viewed in Fig. 1 may be determined to correctly aline the drivers with the nail block openings 22. When the loader arm is in its nail-receiving 75 position the rod 54 rests against the extreme inner end of the slot 56, the driver block at this time being in its operating position. As the loader arm is swung in a clockwise direction, as viewed from above, to transfer its load of nails to the nail block, the rod 80 54 first moves idly in the slot, this movement being to allow for the excess of angular movement of the loader over the amount which it is desired to shift the driver block. Upon arriving at the opposite end of the 85 slot the contact of the rod rotates the sleeve 58 clockwise about the bearing sleeve 60 and through the link 66 shifts the driver block in its ways in advance of the loader block, so that when the latter arrives at the 90 nail-delivering position the drivers are entirely removed from its path. The nails having been supplied to the nail block, the opposite rotation of the loader arm by contact of the rod 54 with the other extremity 95 of the slot 56 returns the driver block to its normal position. Then, when the machine 100 operates, vertical travel of the slot over the rod may occur without interference with the shifting elements for the driver block.

To insure the correct alinement of the drivers with the nail block openings at the 105 time of operation, and yet to permit the travel of said drivers away from and toward their normal position under the control of the loader arm, I lock the driver block in its operating relation, freeing it only when at its extreme of upward travel. Near the center of the upper face of the block 18 is a depression 68 to admit the lower end of a 110 latch rod 70 mounted to slide through a collar 72 screwed into the upper extremity of a vertical bore through the top girt. Surrounding this rod is a helical spring 115 contacting with the collar and with an enlargement upon the rod and serving to urge said rod toward the driver block. The rod 70 extends up through the sleeve 72 and has upon its threaded upper end a nut and lock nut 76 beneath which projects the forked 120

125 130 135

end of a lever 78 fulcrumed upon the top girt. Through an opening in the opposite arm of the lever passes a vertical rod 80, the lower end of which is secured to a yoke 82 fastened to the frame. Upon the extremity of the rod 80 are threaded nuts 84, the under side of the lowermost of which bears upon the lever 78 when the top girt is at its highest point. The elements are so related and 10 the nuts 76 and 84 so adjusted, that at this time the contact of the lever with the nuts 84 rocks the lever about its fulcrum to draw the rod 70 out of the depression 68, thus freeing the driver block for movement by 15 the loader arm. Immediately upon the beginning of downward movement of the top girt the latch bar 70 engages the depression 68 as a result of the travel of the lever 78 away from the nuts 84, locking the driver 20 block in alinement with the nail block openings.

As the operating alinement of the drivers and the openings 22 exists when the loader arm is in its nail-receiving position, it is 25 desired to prevent operation of the actuating mechanism for the drivers at all other times. To this end, there is pivoted to the starting lever 25 a rod 86 adjustable in length by a right and left nut 88. At its top the rod 30 is guided by a head 90 movable in a vertical bore in a casing 91 fixed to the side of the frame. In a connecting lateral bore is mounted a latch 92, this being so located that when the starting lever is raised to the 35 non-operating point the latch lies just below the under side of the head, it being normally urged into the vertical bore beneath the head by a spring 94 between the latch and a plug 96 closing the outer end of the lateral bore. The latch 92 has an upward projection 98 extending into the path of a contact projection 100 from the under side of 40 the loader arm. When this loader arm is in nail-receiving position, at which time the drivers 20 are properly related to the openings 22 in the nail block for the nailing operation, the pressure of the contact portion 100 against the latch projection 98 withdraws said latch from beneath the head 90 45 of the starting lever rod, permitting the lever to be depressed to bring the power mechanism into operation to actuate the drivers. In any other position of the loader arm the travel of the projection 100 away 50 from the latch projection 98 releases the latch, allowing the spring 94 to press it under the head of the starting lever rod, thus locking the machine against actuation.

If the nail block 24 is not so located in its 55 ways that its openings are in perfect alinement with the drivers when they descend, the latter would be broken. When thus positioned, the nail block is locked by a latch 102 operating in a horizontal bore in the 60 frame and pressed into co-operation with a

depression 104 in the block 24 by a spring 106 surrounding its stem 108. At the outer extremity of the latch stem is a finger piece 110, and from this extends a pin 112 for engagement with a depression in the frame. 70 With the pin and frame depression alined, the spring 106 may force the latch 102 into the depression in the nail block, holding this ready for the operation. The latch stem 108 has a lateral projection 114 passing into the 75 casing 91 in a plane beneath the head 90. When the latch pin 112 is in the frame depression and the nail block is locked, the projection 114 is at one side of the head 90, so that the starting lever is freed for de- 80 pression. When, however, the pin 112 is withdrawn and turned to rest upon the frame, thus releasing the nail block latch, the projection 114 lies beneath the head 90, locking this against downward movement 85 and preventing actuation of the machine.

It is to be noted that as this apparatus is arranged, there can be no interference of the nails in the loader mechanism with the drivers, and that, in spite of the movement 90 of said drivers to remove them from the path of the nails, their correct working alinement with the nail block openings is insured by the locking of the driver block at the beginning of its operation. Moreover, 95 as the apparatus can be started only with the loader arm in its nail-receiving position, at which time the drivers are up and locked, and since the starting is also dependent upon the nail block being properly secured in 100 place, breakage of the drivers by contact between them and the nail block is rendered impossible.

Having described my invention, what I claim as new and desire to secure by Letters 105 Patent of the United States is:

1. In a machine of the class described, a holding device, transfer mechanism movable to deliver objects to the holding device and to retreat leaving said objects in the 110 holding device for an operation upon them, a member for operating upon the work, said member co-operating with the holding device and normally lying in the path of objects carried by the transfer mechanism, and 115 means arranged to move the operating member out of the path of the objects.

2. In a machine of the class described, a holding device, transfer mechanism movable to deliver objects to the holding device 120 and to retreat leaving said objects in the holding device for an operation upon them, a member for operating upon the work, said member co-operating with the holding device and normally lying in the path of objects carried by the transfer mechanism, and 125 connections to the transfer mechanism arranged to move the operating member.

3. In a machine of the class described, a nail holding device, movable transfer mech- 130

- anism, movable nail driving mechanism co-operating with the holding device, and connections to the transfer mechanism for moving the driving mechanism into and out of 5 co-operation with the holding device.
4. In a machine of the class described, a holding device, movable transfer mechanism, an operating member co-operating with the holding device and normally lying 10 in the path of objects carried by the transfer mechanism, means arranged to move the operating member out of the path of the objects, and means arranged to determine independently of the transfer mechanism the 15 relation of the operating member and holding device in their co-operation.
5. In a machine of the class described, a holding device, movable transfer mechanism, movable driving mechanism co-operating 20 with the holding device, connections to the transfer mechanism for moving the driving mechanism, and variable means carried by the connections and arranged to determine the relation of the driving mechanism and holding device in their co-operation.
6. In a machine of the class described, a holding device, movable transfer mechanism, movable driving mechanism co-operating 25 with the holding device, and connections to the transfer mechanism for moving the driving mechanism, there being provision for lost motion in the connections.
7. In a heel-attaching machine, a nail block, nail loader mechanism movable over 30 and away from the nail block, drivers alined with the nail block and projecting into the path of the nails in the loader mechanism, and means arranged to move the drivers out of alinement with the nail block in advance 35 of the loader mechanism.
8. In a heel-attaching machine, a nail block, a reciprocatory head, a driver block mounted to move upon the head, oscillatory loader mechanism delivering to the nail 40 block, and connections between the loader mechanism and driver block.
9. In a heel-attaching machine, a nail block, reciprocatory side rods and a head carried thereby, a driver block mounted to 45 move upon the head, a member rotatable about a side rod, loader mechanism mounted to oscillate about the rod, and connections between the loader mechanism and member and between the member and driver block.
- 50 10. In a heel-attaching machine, a nail block, reciprocatory side rods and a head carried thereby, a driver block mounted to move upon the head, a member rotatable about a side rod, loader mechanism mounted to oscillate about the rod, connections between the loader mechanism and member and between the member and driver block, and position-determining means for the driver block carried by the connections.
- 55 11. In a heel-attaching machine, a nail block, reciprocatory side rods and a head carried thereby, a driver block mounted to move upon the head, a sleeve rotatable about a side rod and having a slotted portion, a link connecting the sleeve and driver 60 block, and loader mechanism oscillating about the rod, there being a projection from the loader mechanism co-operating with the slotted portion of the sleeve.
12. In a heel-attaching machine, a nail block, reciprocatory side rods and a head carried thereby, a driver block mounted to move upon the head, a sleeve rotatable about a side rod, a link connecting the sleeve and driver block, a screw threaded through the 65 link for contact with the sleeve, loader mechanism oscillating about the rod, and connections between the loader mechanism and sleeve.
13. In a heel-attaching machine, a nail block, reciprocatory side rods and a head carried thereby, a driver block mounted to move upon the head, a sleeve rotatable about a side rod, a link connecting the sleeve and driver block, loader mechanism oscillating 70 about the rod, and connections having provision for lost motion between the loader mechanism and sleeve.
14. In a machine of the class described, a holding device, movable transfer means co-operating with the holding device, an operating member movable toward and from the holding device and also movable with the transfer means out of and into alinement with said holding device, and retaining 75 means for the operating member against one of its movements, said retaining means being controlled by the other movement.
15. In a heel-attaching machine, a frame, a nail block carried thereby, side rods mounted to reciprocate in the frame, a head fixed to the side rods, a driver block mounted to move upon the head, a latch connecting the head and driver block, a lever fulcrumed upon the head, and a contact member carried 80 upon the frame and extending through the lever.
16. In a machine of the class described, a holding device, means for supplying articles to be held, an operating member movable into co-operation with the holding device and having an independent movement, actuating mechanism for producing one of the movements, and means associated with the supplying means for both controlling the 85 actuating mechanism and effecting the other movement.
17. In a machine of the class described, a holding device, means for supplying articles to be held, an operating member movable into co-operation with the holding device and being also movable out of and into alinement therewith, actuating mechanism for producing the movement of co-operation, and means associated with the supplying 90

means for controlling the actuating mechanism and effecting the movement of alinement.

18. In a machine of the class described, a holding device, an operating member movable into co-operation with the holding device and being also movable out of and into alinement therewith, actuating mechanism for producing the movement of co-operation, transfer mechanism delivering to the holding device, and connections between the transfer mechanism and the operating member and actuating mechanism, the connection to the operating member being arranged to cause its movement.

19. In a machine of the class described, a holding device, an operating member movable into co-operation with the holding device and being also movable out of and into alinement therewith, actuating mechanism for producing the movement of co-operation, a latch for the actuating mechanism, transfer mechanism, and connections between the transfer mechanism and the operating member and latch, the connection to the operating member being arranged to cause its movement into and out of alinement.

20. In a heel-attaching machine, a nail block, a reciprocating head, a driver block mounted to move upon the head, actuating mechanism for the head, a latch for the actuating mechanism, and a nail-loader arranged to move the driver block and latch.

21. In a heel-attaching machine, a nail block, a reciprocating head, a driver block mounted to move upon the head, actuating mechanism for the head, a latch for the actuating mechanism, loader mechanism delivering to the nail block, and connections from the loader mechanism to the driver block and latch arranged to cause the movement thereof.

22. In a heel-attaching machine, a nail block, reciprocating drivers co-operating therewith, actuating mechanism for the drivers, a latch for the actuating mechanism, and loader mechanism delivering to the nail block and having a projection arranged to cause the movement of the latch.

23. In a heel-attaching machine, a nail block, reciprocating drivers co-operating therewith, actuating mechanism for the drivers, a latch for the actuating mechanism, means for normally forcing the latch into co-operation with the actuating mechanism, and loader mechanism delivering to the nail block and acting upon the latch to release the actuating mechanism.

24. In a machine of the class described, a support, a holding device movably mounted thereon, means for retaining the holding device against movement, an operating member movable into co-operation with the holding device, and actuating mechanism for the

operating member, said actuating mechanism being controlled by the retaining means.

25. In a machine of the class described, a support, a holding device separable therefrom, a latch for securing the holding device in place in the support, an operating member movable into co-operation with the holding device, and actuating mechanism for the operating member under the control of the latch.

26. In a machine of the class described, a support, a holding device separable therefrom, a latch for securing the holding device in place in the support and releasing it therefrom, an operating member movable into co-operation with the holding device, and actuating mechanism for the operating member under the control of the latch in the position for release of the holding device.

27. In a heel-attaching machine, a frame, a nail block supported thereon, a latch mounted in the frame and movable out of and into engagement with the block, reciprocating drivers co-operating with the nail block, power mechanism for the drivers, and controlling means for the power mechanism engaged by the latch.

28. In a heel-attaching machine, a frame, a nail block supported thereon, a latch mounted in the frame and movable out of and into engagement with the block, reciprocating drivers co-operating with the nail block, power mechanism for the drivers, and controlling means for the power mechanism engaged by a portion of the latch when said latch is out of engagement with the nail block.

29. In a machine of the class described, a support, a holding device and an operating member relatively movable toward and from each other, both being movable out of and into alinement, actuating mechanism for producing the first-mentioned movement, and means controlling both the holding device and the operating member in their alinement, said controlling means also controlling the actuating mechanism.

30. In a machine of the class described, a support, a holding device and an operating member relatively movable toward and from each other, both being movable out of and into alinement, actuating mechanism for producing the first-mentioned movement, and independent means for controlling the holding device and operating mechanism with respect to their alinement, each of said controlling means co-operating with the actuating mechanism to prevent its action when the holding device and operating member are out of alinement.

31. In a heel-attaching machine, a block having nail-holding openings, drivers movable into the openings, both the drivers and

block being also movable transversely, power mechanism for producing the first-mentioned movement, and means for controlling the transverse movement, said means also controlling the power mechanism.

32. In a machine of the class described, a nail holder, means for operating upon the nails in the holder, nail transfer mechanism 10 delivering to the holder, and a clearing member movable across the holder.

33. In a machine of the class described, a nail holder, means for operating upon the nails in the holder, nail transfer mechanism 15 delivering to the holder, and a clear-

ing member mounted on the transfer mechanism.

34. In a heel-attaching machine, a nail block, co-operating drivers, loader mechanism delivering to the nail block, and a 20 clearing member movable across the nail block after the delivery thereto.

35. In a heel-attaching machine, a nail block, co-operating drivers, a loader arm oscillating over the nail block, and a brush 25 carried by the forward side of the arm and contacting with the block.

In testimony whereof I have signed my name to this specification.

JOSEPH H. POPE.
